UNITED STATES PATENT OFFICE.

WILLIAM HUBERT PAUL BOLL, OF SYDNEY, NEW SOUTH WALES, AUSTRALIA,
 ASSIGNOR TO PHOEMCO LIMITED, OF SYDNEY, NEW SOUTH WALES, AUSTRALIA,
 A COMPANY OF NEW SOUTH WALES.

COLLAPSIBLE CONTAINER.

Application filed February 13, 1922. Serial No. 536,328.

To all whom it may concern:

Be it known that I, WILLIAM HUBERT PAUL BOLL, a subject of the King of Great Britain, residing at No. 4 Bridge Street, 5 Sydney, in the State of New South Wales and Commonwealth of Australia, have invented new and useful Improved Collapsible Containers, of which the following is a specification.

This invention has been specially devised in order to provide improved collapsible open or sealed containers of simple, cheap, handy and efficient construction which may be readily assembled for use and reception 10 of articles or material or for enclosing and sealing the same may be readily collapsed or disassembled to release the contents and may be made heat proof so that in the event of same being subjected to heat the enclosed 15 and sealed contents will not be affected thereby.

According to this invention improved collapsible containers are preferably made cylindrical in cross section with a flat bottom 20 and where required a flat top though they may be made of other shapes which are convex in cross section and are preferably made of sheet metal and comprise a bottom and where required a top and a separable severed and closable wall adapted to engage the 25 edge of the bottom or of the bottom and of the top when the container is assembled and make a tight joint or joints.

An open container such as a cake tin has 30 a bottom with convex and preferably rounded or beaded peripheral edge positioned outwardly of the container and a separable wall consisting of a severed band or hoop having along one longitudinal edge a complementary outward corrugation or groove 35 and at its meeting ends a clamping catch so that when the wall is placed around the bottom and the catch operated the wall will be drawn and clamped tight around the bottom 40 and make a tight joint and the assembled container be held together until deliberately released and collapsed or disassembled.

A sealed container such as a cinematograph film can has the parts before described with the addition of a top the same as the bottom but with the beaded peripheral edges positioned inwardly of the container 45 the wall having complementary outward

corrugation or groove along each longitudinal edge and if desired or required the bottom and the top may be corrugated or otherwise formed in its surface and preferably with outward corrugations or bead like protuberances which strengthen said parts and ensure an air-space between stacked contain- 55 ers. 60

An inwardly stepped and projecting portion or tongue is formed on or affixed to one end of the severed wall so that when its meeting ends are drawn together the tongue 65 forms an inner covering to the joint.

A suitable clamping catch comprises a loop or bail hingedly affixed upon the external face of one end of the severed wall and a lever hinged upon the external face of the 70 other end thereof and having a short rear and slightly outwardly directed tail or extension so that after the lever has been passed through the bail upon one end of said wall and then turned back upon the other 75 end both ends are drawn together with the tongue inwardly across the joint the bottom or the bottom and the top being tightly gripped and the container assembled and sealed the bail being pressed down behind 80 the knuckle of the hinged lever on the opposite end where it grips and remains thus retaining or locking the whole together.

To make a sealed container heat proof as desired or required say for the protection 85 in transit and storage of highly inflammable articles or materials such as cinematograph films the top and bottom are each lined with a layer of insulating material either attached or affixed thereto in any convenient 90 manner or loose and with or without an annular groove in its exposed surface and a false and loose wall of the same or similar material and preferably in the form of an endless band and of a diameter just less than 95 that of the completed container and of a width or height just greater than the internal height of the container between the lined bottom and top and may be with its edges convexed or concaved or flat is placed 100 around the contents in the assembling so that when the container has been assembled and sealed the edges of the false wall will make a good joint with such lined bottom and top.

And in order that the invention may be

readily understood the same will now be described with reference to the accompanying drawings in which Figures 1 and 2 are respectively perspective and partial sectional

5 elevations of an open container such as a cake tin. Figures 3 and 4 are the same respective views of a closed and sealed receptacle such as a film can showing insulating lining. Figure 5 is an elevation of the tongue

10 or overlap on one end of the severed wall and Figures 6 and 7 are plan and sectional plan of the clamping catch.

The open container (Figures 1, 2, 5, 6 and 7) has bottom 8 with beaded peripheral edge 10 positioned exteriorly and separable severed wall 11 with cut and inwardly stepped end or tongue 12 annular groove 13 complementary to the edge 10 usual top edge 14 a loop or bail 15 hinged 15 exteriorly in a knuckle 16 upon one end 17 of the severed wall 11 and a lever 18 hinged exteriorly by trunnions or a pin in a slotted knuckle 19 upon the other end 20 of said wall 11 and having angular tail 21.

20 The closable and sealable container (Figures 3, 4, 5, 6 and 7) has bottom 8 and top 9 each preferably with outward stampings or corrugations 22 and having rounded peripheral edge 10 formed by inwardly turning over the edge 23 of the metal upon and securing the insulating lining 24 which may have annular groove 25 in its exposed surface which edge is positioned interiorly, a separable severed wall 11 having one end 30 cut and inwardly stepped to form a tongue 12 and an annular groove 13 at each edge complementary to the peripheral edges 10, the closing and locking bail 15 and lever 18 as before described and a separable inner 35 wall of insulating material preferably in the form of an endless band 26.

The closable and sealable container may be constructed as before described but without the lining of insulating material.

40 In use an open container is readily assembled by placing the bottom 8 upon a flat surface positioning the severed wall 11 over and around said bottom pressing the ends of said wall towards each other until the 45 stepped end 12 passes behind the other end and the bail 15 may be thrown over the end of lever 18 as in Figure 6 when said lever is turned back until the free end of said bail is pressed down behind the knuckle 19 thus 50 drawing the wall 11 tight upon the bottom 8 making a tight joint and locking the parts 55 of the container together.

When it is desired to disrupt or disassemble the container the lever 18 is pulled 60 out as in Figure 7 and the tail 21 of the lever 18 lifting the bail 15 over the knuckle

19 the wall opens and the container is disassembled.

In enclosing an article or material in a closable container the bottom 8 either plain 65 or with lining 24 thereon is placed upon a flat surface with the beaded edge 10 upwards the article or material is placed upon said bottom the wall 26 of insulating material if required is placed upon said lining 70 24 or seated in the groove 25 when same is formed in the lining the top 9 either plain or with lining 24 thereon is then positioned upon the goods or when the wall 26 is used upon the top edge thereof which edge will 75 seat in the groove 25 when same is formed in the lining and the severed wall 11 placed around the whole and its ends drawn, clamped and locked together as before described.

The outward stampings or corrugations 80 22 in the bottom 8 and top 9 serve to strengthen said parts and ensure an air space being left between the containers when a number are packed or stored.

I claim:

1. An improved collapsible closed container consisting of a bottom and a top each provided with an inturned beaded edge, bottom and top lining pieces engaged and retained respectively by the beaded edges 90 on the bottom and top and also provided with receiving means on adjacent faces, a ring-like side lining piece engaged by the receiving means in the bottom and top lining pieces, a separable severed wall 95 provided with complementary corrugations about and adjacent the longitudinal edges for engagement with the beaded edges of the bottom and top respectively, and means for drawing said severed wall into tight engagement upon said bottom and top and for holding the ends of said wall together and in addition locking the ring-like side lining piece within the receiving means in the bottom and top lining pieces.

2. A collapsible closed container including a top, a bottom, a contractible severed side wall for embracing the edges of the top and bottom, a lining of insulating material including a top piece, a bottom piece and a unitary separable ring-like side piece, means on the top and bottom for respectively retaining the top and bottom pieces of the lining, and the top and bottom lining pieces being provided with means for accommodating the side lining piece and for locking said piece subsequent to the engagement of the contractible severed side wall with the top and bottom pieces.

Dated this eleventh day of January one 120 thousand nine hundred and twenty two.

WILLIAM HUBERT PAUL BOLL.
